CLAIM

The ornamental design for a cultivating hoe, as shown and described.

DESCRIPTION

FIG. 1 is a view in perspective, looking along the length of the handle and front side of the blade constituting the present invention;

FIG. 2 is a front elevational view of the cultivating hoe;

FIG. 3 is a back elevational view of the cultivating hoe;

FIG. 4 is an elevational view of the cultivating hoe as shown in FIG. 2, looking from the left thereof;

FIG. 5 is an elevational view of the cultivating hoe as shown in FIG. 2, looking from the right thereof;

FIG. 6 is a top plan view thereof; and,

FIG. 7 is a bottom plan view thereof.
